LAMP SOCKET

Leonard O. Erikson, Malden, Mass.

Application August 18, 1934, Serial No. 740,449
Renewed March 4, 1937

1 Claim. (Cl. 176—29)

This invention relates to lamp sockets and more especially to lamp sockets for connecting a relatively long lamp having metallic end closures in circuit with a supply system.

5 The object of my invention is to provide a socket whereby a tubular lamp may be readily connected to and disconnected from the circuit and whereby fire hazard and danger to the person are reduced.

10 My invention comprises an insulating cap containing a resiliently-controlled movable contact member constructed to snap over the end closure of a tubular lamp and supporting means whereby the caps on the ends of the lamp are held in desired position, each said supporting means enclosing a connector arranged for engagement with the contact members and for connection to the supply system.

The metallic parts of the sockets and their supports are enclosed within insulating material to reduce fire hazard and danger of injury to the person.

An exemplification of my invention is shown in the accompanying drawing in which—

25 Figure 1 is a side elevation;
Fig. 2 is a central longitudinal section;
Fig. 3 is an end view of the socket;
Fig. 4 is a transverse section taken on the line 4—4 of Fig. 2;

30 Fig. 5 is a fragmentary longitudinal section showing the use of my invention for connecting a pair of lamps in tandem.

In the particular drawing selected for more fully illustrating the principle of my invention, 35 10 is a metallic channel such as ordinarily used for enclosing the conductors in show-case lighting systems and the like. The channel is provided with spaced apertures 11, through which project the ends of a pair of insulating housings 12, such housings being shouldered longitudinally, as indicated at 13 and provided with flanges 14 which rest on the upper face of the channel. By means of screws 15 the housings 40 are securely held to the channel.

45 Each housing is provided with a transverse bore 16 intersecting a longitudinal bore 17 disposed within which is a connector 18 provided at its lower end with binding-post means 19 and at its upper end with a head 20 disposed within or registering with the transverse bore aforesaid. Any suitable means such as the screw 21 may be employed to secure the connector within the housing and preferably the screw 50 hole is filled with insulating cement, as indi-

cated at 22, after the screw has been placed in position.

As indicated in Figs. 1 and 2, a plug 23 of insulating material may be employed to close the outer socket formed by the transverse bore 16. 5

An insulating cap 30 is provided with a plug 31 receivable within and closely fitting one of the sockets formed by the transverse bore 16 in the housing. Disposed within the cap is a contact member 32, preferably of resilient material, which 10 is shaped to receive and snap over the metallic end closure 34 of the tubular lamp 35. In the present instance the contact member is shown as a four-arm spider centrally disposed within the cap and controlled by the spring 33 interposed 15 between the base of the cap and the disc portion of the spider. Through the central bore of the spider the headed stud 36 passes and extends through the plug 31, its outer end being in engagement and electrical contact with the connector 20. The headed stud constitutes a means for limiting the forward movement of the contact member and preferably is arranged so that said member cannot move beyond a point within the open end of the cap so that the ends of the 20 25 spider will not project beyond such open end. Obviously the spring will permit limited longitudinal movement of each cap with respect to the lamp.

In the drawing the lamp is shown as having a 30 filament 37 connected electrically by the pins 38 and supports 39 to the end closures 34. An insulating block 40 is interposed between the members 39 and the support 41 for the pins 42. The lamp shown in the drawing is of a well-known 35 type and constitutes no part of the present invention.

In order to connect the tubular lamp in circuit, the caps are placed over the ends thereof, the contact members 32 snapping over the lamp 40 closures and the caps thereby being retained on the lamp. The plug 31 of one of the caps may then be inserted in the socket 16 of one of the housings 12, whereupon the cap at the other end of the lamp may be moved back against the 45 resistance of the coiled spring a distance equal to the length of the plug, the latter brought into register with the housing socket and then released, whereupon the spring forces said plug into said socket and the circuit through the 50 lamp is then completed by way of the two connectors, the flanged studs and the contact members; or the operator may grasp both caps, push them toward each other against the resistance of their respective springs so that the ends of 55

the plugs will clear the proximate ends of the 5 housings and then insert the former in the latter. It will be noted that the separation of the proximate ends of the cap is less than the length 10 of the lamp so that none of the metallic members enclosed within a cap is exposed, and also that the distance between the outer ends of the 15 plugs is greater than the separation of the proximate faces of the housings 12 by substantially twice the length of a plug, the length of each plug being substantially the amount of permissible movement of a cap with respect to the lamp.

- To remove a lamp from circuit one of the 15 caps is drawn back over the lamp until the end of a plug clears its socket, whereupon the lamp may be lifted out of its support; or both caps may be pushed back simultaneously so that both 20 plugs will clear their sockets.
- 20 In order to connect two lamps 35 and 35' in tandem, the plug 23 is removed and the plugs on the ends of the caps 30, 30' inserted in the registering sockets of the support 12. In this way two or more lamps may be connected in

tandem mechanically and in parallel with the electric circuit.

It will be obvious that all of the current-carrying members of the lamp, the socket and the 5 socket supports are fully enclosed by insulating material and therefore cannot come into contact with the user.

Having thus described illustrative embodiments of my invention without however limiting the same thereto, what I claim and desire to 10 secure by Letters Patent is:

The combination with a tubular lamp having metallic end closures electrically connected to the filament thereof, of a pair of oppositely-disposed insulating caps disposed on the respective 15 ends of said lamp, and a pair of conducting members of resilient material, each disposed within one of said insulating caps and resiliently secured to said end closures, the proximate ends of said insulating caps extending over and beyond said metallic end closures and conducting members, respectively. 20

LEONARD O. ERIKSON.
